[57] CLAIM

The ornamental design for a table base, as shown and described.

DESCRIPTION

FIG. 1 is a front perspective view of a table base showing our design;

FIG. 2 is a top plan view;

FIG. 3 is a rear elevation view;

FIG. 4 is a right side elevation view; and,

FIG. 5 is a front elevation view thereof.

The side of the table not shown is a mirror image of the side shown in FIG. 4.

The design is characterized by the combination of a table base including a circular top plate, column, rectangular pedestal and adjusting switch of triangular configuration as best shown in FIG. 1.
